CLAIM

The ornamental design for a tablet case, as shown and described.

DESCRIPTION

1. Tablet case
  - 1.1 : Perspective
  - 1.2 : Perspective
  - 1.3 : Front
  - 1.4 : Back
  - 1.5 : Left
  - 1.6 : Right
  - 1.7 : Top
  - 1.8 : Bottom
  - 1.9 Enlarged view of the portion taken at line **9** in Fig. **1.1**;
  - 1.10 Enlarged view of the portion taken at line **1.10** in Fig. **1.1**;
  - 1.11 : Perspective view in folded state
- The broken lines depict portions of the structure that form no part of the claim. The dash-dot-dash lines depicting the cut lines and labels “**9** and **10**” in Fig. **1.1** also form no part of the claim.
